UNITED STATES PATENT OFFICE.

NELS A. ANDERSON, OF WARREN, OHIO, ASSIGNOR TO THE HARRIS AUTOMATIC PRESS COMPANY, OF NILES, OHIO, A CORPORATION OF OHIO.

TYMPAN-CLAMP.

1,295,098.

Specification of Letters Patent.

Patented Feb. 25, 1919.

Application filed April 21, 1915. Serial No. 22,890.

To all whom it may concern:

Be it known that I, NELS A. ANDERSON, of Warren, in the county of Trumbull and State of Ohio, have invented certain new and useful Improvements in Tympan-Clamps; and I do hereby declare the following to be a full, clear, and exact description of the invention, such as will enable others skilled in the art to which it appertains to make and use the same.

The primary object of this invention is to enable a draw-sheet or tympan to be self alining and self locking as a reel-rod is rotated to make such sheet or tympan taut on a printing element.

A further object is to render unnecessary the use of clamps for attaching a blanket or draw-sheet to its adjusting reel rod.

In the accompanying drawings, Figure 1 is a transverse sectional view of a press cylinder showing my improved reel rod. Fig. 2 is a front view of the press cylinder. Fig. 3 is a diagrammatic view showing the end of the sheet in initial engagement with the reel-rod before the latter is rotated. Fig. 4 is a similar view showing the reel rod in the position it occupies as it completes its rotation. Figs. 5 and 6 show slight modifications.

Referring to the drawings, 1 designates an impression-cylinder of a printing press which is shown by way of illustration, since my present improvement may be employed in connection with a reciprocating bed or other printing element of a printing press. 2 is a reel rod which I have shown as mounted in a cut-out portion of the cylinder and by which one end of the tympan or draw-sheet 3 is held and drawn taut, the sheet at its other end being secured to the cylinder by any suitable means, such as a clamping plate 3^a. According to my present invention the reel-rod is formed with a slot extending longitudinally thereof and parallel to its axis and through which slot the draw sheet, after being wrapped around the press cylinder, is projected, whereupon by turning the reel-rod the sheet may be properly alined on the cylinder and automatically locked to the reel-rod. The free end of the sheet is extended through the slot and by being bent back upon itself is locked to the reel-rod without the use of clamps such as have heretofore been employed for this purpose.

According to the construction shown in Figs. 1 to 4, the slot is formed by means of a thin metal strip 4 secured at its bent ends to a face of the reel rod, the space between the latter and the strip constituting a slot. The reel rod is shown as formed with a plurality of flat faces, the number being immaterial, that is to say, the reel rod in cross section may have six sides, more or less, as shown in Figs. 3 and 4, or it may be square in cross section as shown in Fig. 5 or substantially cylindrical, with a single flat side, as shown in Fig. 6. The reel rod is provided with the customary ratchet 5 with which a holding pawl 6 is designed to engage.

In practice, the draw-sheet after being secured at one end to the cylinder is wrapped around the latter, and the projecting end is then passed through the slot in the reel rod, being simply pulled straight through by hand until it is snug around the cylinder. The operator then releases his hold on the end of the sheet and turns the reel rod. By reason of the slight friction of the walls of the slot the sheet will be kept flat and straight until the first revolution of the reel rod is nearly completed, whereupon the end of the sheet is doubled back (see Fig. 4) by contact with the upper or stretched portion which immediately begins to tighten under the locking strain. Hence by means of my invention the sheet is rendered self alining and self locking, being held to the reel rod without the use of clamps as heretofore required.

It will be understood that I do not confine myself to the means shown and described for carrying out my invention. While the slot may, as stated, be formed in the reel rod, yet I prefer to provide such slot by the spaced metallic strip, and in this connection it should be noted, that, if desired, one end of the strip may be detachably held to the reel rod so as to permit it to be raised in inserting the end of the draw sheet between the reel rod and the strip.

The advantages of my invention will be readily appreciated by those skilled in the art, and it will be seen that by means thereof the draw sheet may be effectively secured in place and an even surface maintained on the printing element, the sheet itself being self alining relatively to the latter, after being once inserted through the slot of the reel.

rod and automatically locked to the latter as the same is rotated.

I claim as my invention:

1. In a printing press impression cylinder having a longitudinal recess, a clamping plate adapted to bind one end of a draw sheet, and a tension reel located in said recess, said reel having a spaced apart element, a slot being formed between said element and said reel, and through which slot the free end of a draw sheet may be loosely passed, such end being automatically turned back upon itself and locked to the reel as the latter is rotated.
- 10 2. In a printing press impression cylinder having a longitudinal recess, a clamping plate adapted to bind one end of a draw

sheet, and a tension reel located in said recess and having one or a plurality of flat sides and a strip paralleling the reel to form 20 a slot through which the opposite end of a draw sheet is adapted to be loosely passed to permit automatic adjustment of the sheet as such reel is initially rotated, the sheet being automatically caused to bind against 25 said strip and on said reel as the latter is rotated.

In testimony whereof, I have signed this specification in the presence of two subscribing witnesses.

NELS A. ANDERSON.
